Andrew Goodyear

UNITED STATES PATENT OFFICE.

ANDREW GOODYEAR, OF SPRINGPORT, MICHIGAN.

IMPROVEMENT IN MACHINES FOR CUTTING BARREL-HOOPS.

Specification forming part of Letters Patent No. 57,120, dated August 14, 1866.

To all whom it may concern:

Be it known that I, ANDREW GOODYEAR, of the town of Springport, in the county of Jackson and State of Michigan, have invented certain new and useful Improvements in Machines for Making Hoops for Barrels, or for analogous uses; and I do hereby declare that the following is a full, clear, and exact description of the construction and operation of the same, reference being had to the annexed drawings, making a part of this specification, in which—

Figure 1 is a side elevation. Fig. 2 is a cross-section in the line *x* and elevation of one end of the machine. Fig. 3 is an enlarged section of a portion in said line *x*. Fig. 4 is a partial elevation of cutting-knife detached. Fig. 1 is broken to indicate disproportionate length.

Similar letters of reference indicate corresponding parts in all of the figures.

My invention relates to a mode of cutting hoops for barrels from boards, so as to leave one edge thinner than the other, to adapt it to the bilge, or for cutting lath with beveled edges, which, when nailed to the wall, will leave dovetail-formed spaces between them, so as to better secure the plaster, or for other analogous uses.

The invention consists in the use of a simple lever acting on a sliding hinged table against a clamped horizontal or oblique cutter, in connection with arrangements for properly tilting said table and for safely discharging any article, when cut, from the machine; and the better to enable others skilled in the art to construct my said invention, I will now proceed more particularly to describe it.

My mode of cutting resembles the mode in use for cutting staves, a board of proper thickness well steamed being forced up against a thin cutting-knife substantially in the manner of a stave-bolt. To avoid, therefore, any redundancy of language, I propose to limit my detailed description to such arrangements of parts only as form distinctive features in my machine for the special uses indicated.

As I usually construct my machine, a strong cutter-beam of cast-iron, *A*, bolted to two standards, *B*, constitutes the frame. The cutter-beam may be secured by adjusting bolts *b* through the flanges *f*, and made adjustable

laterally by slots in the standards. The beam is formed in two halves bolted together, between which the cutter-knife *C'*—a long, thin, sharp-edged plate of steel—is firmly pinched.

To prevent the cutting-knife *C* from springing I cast openings *o* and side grooves in the beam-plates, in which grooves the nuts *n* are inserted, provided with set-bolts *e*, which form a solid backing for the knife, and can be screwed down to compensate for wear.

I do not wish, however, to confine myself to setting the cutting-knife exactly parallel with the board to be cut; but, when necessary, I propose to so connect such knife and its beam with the standards as to form any suitable angle for the purpose of giving more or less of a shearing-cut, in which case said knife would be fastened by countersunk-headed screws flush with the face of a single solid beam, as may be clearly seen in Fig. 4, where *C²* represents the knife.

D is a vibrating lever, cast on, or otherwise secured to an angle rock-shaft, *E*, having its bearings *r* in the standards, and operating, by any desired number of pressure-bars, *F*, a sliding platen, *H*, which is guided in the grooves *G*.

T represents the feeding-table, on which the stuff to be cut rests. It is simply a flat iron plate hinged to the platen in close contact, immediately below the cutting-knife, and when used, as in Fig. 1, a narrow groove, *g*, should be formed near the back edge, and filled with a strip of wood, as a line of contact with the said knife when finishing the cut.

In order to give the proper bevel or taper to the article cut without the trouble of turning over the board, I elevate and depress the feeding-table alternately from a horizontal line, just previous to each cut, in the following manner: To one end of the sliding platen *H* is connected a projecting arm, *J*, which carries two spur-wheels, *S'* and *S²*, gearing into each other and revolving freely upon studs secured to said arm. The wheel *S'* is only half the diameter of *S²*, and has a small fly-wheel, *W*, cast or otherwise attached to it, which fly carries a crank-pin, *p*, so as to be capable of adjustment for any required length of stroke. A rod, *R*, free to vibrate on the projecting arm-pin at *v*, is connected to the said crank-pin by a strap in the ordinary way.

The wheels are so arranged that the front part of the hinged feeding-table will rest upon the edge of a cam-plate, *i*, fastened to the wheel *S*², the semi-periphery of which plate projects a distance equal to the required lift of the table. The cam-shaped projecting portion may be fastened separately, so as to be readily detached and replaced by another section having more or less throw, or a separate cam-piece may be provided with slots, and adjusted and secured by set-screws.

Now, when the crank-pin *p* is so adjusted that the radius of its path will just equal the travel of the platen the up-and-down movement will, aided by the centrifugal force generated by the fly, produce a continuous motion of the gear, the cam making a semi-revolution for every whole revolution of the crank-pin or corresponding up-and-down motion of the cutting-knife, and thus elevate and depress the table alternately at every cut, so as to change the angle of the board with the line of motion of the platen, and, without shifting the board, produce a hoop, lath, or other article, with one edge or side thinner or narrower than the other.

L represents guide or gage rods, attached to an adjustable bar, *M*, to gage the thickness of the article to be cut, and to prevent such article from dropping back on the table after being cut I attach to the guides a spring, *j*, the operation of which is clearly shown in Fig. 3.

The edge of a board, *N*, being pressed against the springs, forces them back into recesses (not shown) in the guides, and comes in contact with them; the platen, lifting the board against the cutting-knife *C'*, cuts off a hoop, *h*, when the spring recovers its first position and supports the hoop on a lip until the next cut hoop pushes it off and takes its place, &c.

The vibrating lever *D* may be operated by a pitman (not shown) connected at one end to the adjustable pin *F*, and at the other to the adjustable pin of a crank driven by any requisite and convenient motive power. By applying the cam *i* to one edge of a table arranged to vibrate horizontally, and a spring to the other, shingles may be readily cut in my machine, or any article having slight horizontal angles.

I do not claim cutting hoops or other articles from a steamed board by forcing such board against a stationary knife, so as to make either a direct or shearing cut; nor do I claim, broadly, tilting or vibrating the table on which such board lies.

What I claim as my invention, and desire to secure by Letters Patent, is—

1. The use of the cam *i*, in combination with the gear-wheels *S'* *S*², fly-wheel *W*, and vibrating rod *R*, arranged and operated, relatively with each other and with the platen, table, and frame, substantially as and for the uses specified.

2. The mode of securing the cutter-knife *C'* by clamping it between the half-beams *A*, in combination with backing-bolts *e* and nuts *n*, substantially as herein described.

3. The employment of a spring, *j*, in combination with recessed guides *L*, for safely discharging a hoop, *h*, or other cut article, as set forth.

ANDREW GOODYEAR.
